UNITED STATES PATENT OFFICE.

JAMES H. RAND, OF NEWTON, MASSACHUSETTS.

INDEX.

1,288,188.

Specification of Letters Patent. Patented Dec. 17, 1918.

Application filed October 29, 1917. Serial No. 199,019.

To all whom it may concern:

Be it known that I, JAMES H. RAND, citizen of the United States of America, and resident of Newton, in the county of Middlesex and State of Massachusetts, have invented new and useful Improvements in Indexes, of which the following is a specification.

This invention relates to card indexes of the overlapping card, visible index type, and has to do mainly with novel and improved devices for supporting cards in the frame.

In the accompanying drawings which illustrate a preferred embodiment of the invention—

Figure 1 is a front elevation of part of an index containing the invention;

Fig. 2 is a perspective view of one of the individual supporting and spacing bars;

Fig. 3 is a plan view of one of the bars with the wire on which the card is hung;

Fig. 4 is a front elevation of one of the wires and its attached card;

Fig. 5 is a front elevation of a modification; and

Fig. 6 is a sectional detail on line 6—6 of Fig. 1.

The usual frame or panel A, preferably made of sheet metal, is provided with the usual bent flanges a at its side edges, constituting inwardly facing channels for receiving the ends of the card supporting devices.

Each card supporting device comprises a bar B of resilient sheet metal, bent over upon itself at each end as shown at b and thence inwardly toward the face of the bar as shown at b'. The inwardly bent ends b' are provided with holes or apertures b² which constitute sockets for the ends of card supporting wire D.

The card C is attached at its upper edge to the wire D by being folded over the wire, and the folded margin c (Fig. 6) fastened, preferably by paste or cement to the body of the card, so that the fold of the card fits snugly around the wire. The card may however be shifted lengthwise of the wire, or the wire may be wholly removed.

The ends of the bars B which are resilient are inserted in the channels of the frame by springing the bars at the middle to contact the distance between the ends sufficiently to pass the ends past the flanges a

and into the channels. The bent-over ends b fill, or approximately fill the channels and afford a sufficiently wide bearing surface at the top and bottom of each bar to prevent any possibility of one bar overriding another. The bars are adjustable lengthwise of the frame, and are interchangeable one with another.

The ends of the wires D are similarly inserted into the opposed holes or sockets at the ends of the bars by bending or springing the wires at their middle, the inherent resilience of the wire causing it again to straighten out after the ends have been introduced into their holes.

To inspect any card the next overlying card, and those above it, are swung upwardly on their hinges, one member of each hinge being the socket at the end of the bar B, and the other hinge member being the end of the wire.

The inwardly bent ends b' of the several bars form substantially continuous walls which close the channels of the frame and normally prevent any accidental lateral displacement of the cards on their several wires. Should it be desired however to provide for lateral displacement of the cards so that a particular card which it is desired to consult may serve as a signal and guide to its location, the modification illustrated in Fig. 5 may be used, wherein each card is cut away at the top as shown at c' so that it may be shifted lengthwise of its wire a limited distance as illustrated at c², for instance.

The cards C may be cards or sheets on which entries and records of various sorts are kept, or they may be holders for other cards in which case a pocket E of transparent sheet celluloid or other suitable material is provided at the lower edge of each card to receive a suitable card insert. In either case the bars will hold the cards in suitable spaced relation to expose the margins of the cards for indexing purposes.

I claim:—

1. An index comprising a frame, means disposed along each side margin of the frame having a series of separate and independent inwardly facing sockets spaced apart, a series of card supporting wires having their ends mounted in opposite sockets, and a series of cards supported by said wires.

2. An index comprising a frame having

inwardly facing channels, a series of bars having their ends mounted in the channels, a series of card supporting wires having their ends pivoted to the several bars and a series of cards supported by the wires.

3. An index comprising a frame having inwardly facing channels, a series of bars having their ends mounted in the channels, the bars having socket members at each end, 10 a series of card supporting wires having their ends in pivotal engagement with the socket members, and a series of cards supported by the wires.

4. An index comprising a frame having 15 inwardly facing channels, a series of bars having their ends mounted in the channels, each bar being bent over and inwardly upon itself at its ends and the inwardly bent ends being provided with sockets, a series of supporting wires having their ends mounted in 20 said sockets, and a series of cards supported by the wires.

5. An index comprising a frame having inwardly facing channels, a series of bars 25 of resilient metal, each bar being bent over and inwardly upon itself at its ends and the inwardly bent ends being provided with apertures constituting sockets, the bent over ends being removably mounted in the channels of the frame, a series of supporting 30 wires having their ends mounted in said

apertures, and a series of cards supported by the wires.

6. A card supporting device for indexes comprising a bar of sheet metal bent over 35 and inwardly upon itself at its ends, the inwardly bent ends being provided with apertures constituting sockets and a wire extending between said inwardly bent ends having its ends mounted in said apertures. 40

7. A card supporting device for indexes comprising a bar having a portion near each end bent transversely of the plane of the bar, said bent portions being provided with apertures forming sockets, and a wire extending 45 between said bent portions having its ends mounted in said sockets.

8. A card supporting device for indexes comprising a bar having opposed socket members at its ends provided with apertures therein, and a wire extending between 50 and mounted at its ends in the apertures of said socket members.

9. A card supporting device for indexes comprising a bar adapted to be supported at 55 its ends in the guide channels of a frame, and a card supporting wire removably attached to said bar.

Signed by me at Boston, Massachusetts this twenty-second day of October, 1917.

JAMES H. RAND.
